DRILL

George J. Barrett and Sosthene Robichaux,
Houston, Tex.

Application May 10, 1937, Serial No. 141,589

6 Claims. (Cl. 255—71)

This invention relates to a drill and has particular relation to that type of drill to be used in drilling wells through rock or other hard formation.

5 It is an object of the invention to provide a drill having a plurality of side cutters for disintegrating the formation at the outside of the bore as the drill progresses and having suitable cross-rollers at the lower end of the drill for 10 disintegrating the material at the bottom of the bore.

In a preferred embodiment of the invention more than two side cutters are provided, there being preferably four side cutters as shown. 15 The major portion of the work is performed by the rolling side cutters and they are subjected to severe wear. For this reason the number of side cutters has been increased over the number of side cutters commonly employed in rock 20 drills so that the side cutters will not be so quickly worn away and the gauge of the bore thus reduced. The drill also embodies a novel construction for mounting the cross-rolling cutters for disintegrating the central portion of the 25 bore.

It is another object of the invention to provide a drill of the character described that is of simple construction and which may be readily assembled or dismembered for repairs and 30 placements.

With the above and other objects in view the invention has particular relation to certain novel features of construction, operation and arrangement of parts, an example of which is given in 35 this specification and illustrated in the accompanying drawing, wherein—

Figure 1 shows a side view of the drill, partly in section.

Figure 2 shows a side view thereof, taken at 40 right angles to the view shown in Figure 1 and shown partly in section.

Figure 3 shows a lower end view, and

Figure 4 shows a fragmentary, sectional view of another embodiment.

45 Referring now more particularly to the drawing wherein like numerals of reference designate the same parts in each of the figures, the numeral 1 designates the drill head which is upwardly extended and formed with the shank 2 for connection to the drill stem or other driving member. The shank and head have the usual passageway 3 downwardly therethrough for the discharge of the drilling fluid. The lower end of the head is formed with the spin- 50 die anchors 4, 4 and 5, 5, which are spaced apart

around the lower end of the head and whose inner sides present the flat bearing faces 6, 6 and 7, 7, which diverge downwardly.

Converging inwardly and downwardly from the anchors 4, 4 are the spindles 8, 8 and converging inwardly and downwardly from the anchors, 5, 5, are similar spindles 9, 9. The outer ends of these spindles, in assembly, may be fitted through bores as 10 through the corresponding anchors 4, 5, and then welded in place, 10 as more clearly shown in Figure 1.

Frusto-conical shaped rollers 11, 11 are rotatably mounted on the spindles 8 and frusto-conical shaped rollers 12, 12 are rotatably mounted on the spindles 9. In a preferred embodiment of the invention the rolling cutters 11 are oppositely disposed and the rolling cutters 12 are also oppositely disposed as more clearly shown in Figure 3. These cutters are provided with external cutting teeth which roll about 20 the outer portion of the bottom of the bore and disintegrate the hard material encountered.

There is a bridge 13 whose upper end is circular and concaved, said upper end being fitted into a correspondingly shaped countersunk 25 groove 14 around the lower end of the passageway 3 and preferably welded in place. This bridge has the depending legs 15, 16 which are spaced apart and which have transversely aligned bearings to receive the spindle 17. One 30 end of this spindle may be an enlarged head 18, if desired, and the ends of the spindle are arranged adjacent, but are not connected to, the opposing faces 19, 19, into which the inner ends of the spindles 8 are formed.

35 Mounted on the spindle 17 between the legs 15, 16 there is a rolling cutter 20. This rolling cutter, as shown, is approximately frusto-conical shape in form with its smaller end located approximately at the axis of the drill and abutting the leg 15 so that the rolling cutter 20 will cut away or disintegrate the center of the bore as the drill is rotated. On the opposite ends of the spindle 17 and at the outer sides of the legs 15, 16 are the rolling cutters 21, 22. The 40 rolling cutter 21 is so located that it will disintegrate that portion of the bottom of the bore left between the cutters 20 and 22 and the cutter 22 is so located that it will disintegrate that portion of the formation left between the cutter 45 21 and the cutters 12.

45 It will be noted that the cutters 12 are extended inwardly further than the cutters 11, the arrangement being such that the cross-rolling cutters 20, 21, 22 will traverse the entire area 50 55

at the bottom of the bore not disintegrated by the side cutters 11, 12.

Since the major portion of the work of the drill will be performed by the side cutters 11 and 12, a greater number of said side cutters have been provided than is now commonly used so that each side cutter will be subjected to less wear than would otherwise be the case and the full diameter of the bore will thus be maintained. In the embodiment shown in Figure 4 the bridge 13a is provided with only the depending leg 15 in which the spindle 17 has a bearing and in this form said spindle 17 may have one end, or both ends if necessary, welded to the adjacent spindle, or spindles, 8. The bridges 13, 13a are provided with suitable ducts as 23 whereby the flushing fluid may be delivered onto the respective cutters.

If desired, the leg 15 may be laterally braced 20 by means of the braces 24 which are welded thereto and to the inner end of the spindles 9 as more clearly shown in Figure 3.

As indicated in Figure 1 the side rolling cutters 11, 12 are mounted to rotate on anti-friction 25 rollers 25 and ball bearings 26.

In assembly the cutters may be slipped over the spindles on which they are mounted and the rollers 25 inserted into their raceways during this process. The raceways in which the balls 30 26 ride will then be in registration and these balls may be inserted into their raceways through suitable gates, left in the spindles for that purpose and the gates then plugged up by welding in the usual manner. The spindles may then be 35 inserted through the bores 10 and welded therein and the bridge with the cross-rollers assembled thereon may be welded into place and the drill thus completed.

It may be found most practical to make the 40 bores 10 in the form of slots extending down to the ends of the anchors 4, 5 in which case the rolling cutters 11 assembled on their spindles 8 and the bridge 13 with the cross-rolling cutters mounted in place thereon may be inserted as a 45 unit into place, the outer ends of the spindles 8 passing up into said slot-like bores 10 and these parts may then be permanently welded in position and the side cutters 12 assembled on their spindles 9 may then be inserted into the position 50 shown in Figure 2 and the spindles 9 welded in place and thereafter the braces 24 may be formed by the welding process.

The drawing and description disclose what are now considered preferred forms of the invention 55 by way of illustration only, while the broad principle of the invention will be defined by the appended claims.

What we claim is:

1. A drill comprising a head, spindle anchors 60 thereon whose inner sides diverge downwardly, spindles on the anchors which converge down-

wardly, frusto-conical rolling cutters on the spindles, a transverse spindle on the lower end of the head whose ends are arranged adjacent the downwardly converging spindles, means independent of the downwardly converging spindles and supporting the cross-spindle and rolling cutters on the transverse spindle.

2. A drill comprising a head, four outside frusto-conical rolling cutters mounted to rotate on the head and arranged to disintegrate the formation at the bottom of a well bore and some extending inwardly further than the others and rolling cutters on the drill mounted to rotate on a transverse axis and arranged to disintegrate the formation at the central portion of the bore.

3. A drill comprising a head, four downwardly and inwardly converging spindles thereon, outside frusto-conical rolling cutters on said spindles arranged to disintegrate the formation at the outer portion of the bore, each of said cutters being of a unitary structure and some extending inwardly further than the others, a leg anchored to the head and depending therefrom, means connecting said leg to some of said spindles, a transverse rolling cutter support on the leg whose ends are adjacent other of said spindles and cross-rolling cutters on said support arranged to disintegrate the formation at the central portion of the bore.

4. A drill comprising a head, four outside rolling cutters mounted to rotate on the head and arranged to disintegrate the formation at the bottom of the well bore, each cutter being of a unitary structure and two oppositely disposed of said cutters extending inwardly toward the axis of the drill further than the other of said cutters and rolling cutters on the drill mounted to rotate on a transverse axis and arranged to disintegrate the formation left at the central portion of the bore by said outside cutters.

5. A drill comprising a head, four spindle anchors depending from the head and spaced apart approximately a uniform distance around the head, downwardly converging spindles on the anchors, frusto-conical shaped cutters mounted to rotate on said spindles, each cutter being of a unitary structure and two opposing cutters extending inwardly further toward the axis of the head than the other two cutters.

6. A drill comprising a head, a transverse spindle at the lower end of the head, rolling cutting means on the spindle arranged to disintegrate the formation at the central portion of the bore, four outside frusto-conical rolling cutters on the head spaced apart in approximately uniform distance around the head, two opposing rolling cutters extending inwardly toward the center of the head further than the other two of said rolling cutters.

GEORGE J. BARRETT.
